CLAIM

The ornamental design for a scale with an extendable length measuring instrument, as shown and described.

DESCRIPTION

1. Scale with an extendable length measuring instrument
- 1.1 : Right
- 1.2 : Front
- 1.3 : Left
- 1.4 : Back
- 1.5 : Perspective
- 1.6 : Bottom
- 1.7 : Top
- 1.8 : Perspective view with extended measuring stick
- 1.9 : Perspective view with extended measuring stick
- 1.10 : Perspective detail view
